(57) **CLAIM**

The ornamental design for a display screen or portion thereof with graphical user interface, as shown and described.

DESCRIPTION

FIG. 1 is a front view of a first image in the sequence for a display screen or portion thereof with graphical user interface;

FIG. 2 is a front view of a second image thereof; and,
FIG. 3 is a front view of a third image thereof.

The broken line showing of the tablet and display screen is for environmental purposes only and forms no part of the claimed design. The broken line showing of text, various icons, hand, and remainder of the graphical user interface is for environmental purposes only and forms no part of the claimed design.

The appearance of the transitional image sequentially transitions between images shown in FIGS. 1 through 3. The process or period in which one image transitions to another image forms no part of the claimed design.
